ABSTRACT

Parallax barrier supporting means comprising substantially flat, rectangular bimetallic elements are disclosed. The elements are attached to the upper portion of the barrier frame and have depending springs attached thereto. The springs have apertures formed therein to mate with studs formed on the tube envelope inner wall.

SHADOW MASK SUPPORT COMPRISING FLAT, BIMETALLIC ELEMENT ATTACHED TO INWARDLY PROJECTING FRAME FLANGE

BACKGROUND OF THE INVENTION

This invention relates to color cathode-ray tubes and more particularly to temperature compensating supporting systems for the parallax barrier mounted therein.

In conventional color cathode-ray tubes in use today a mosaic, cathodoluminescent phosphor screen is formed on the interior surface of the viewing screen. Positioned at a point remote therefrom is an electron source formed to provide an electron beam or beams for exciting the phosphors to luminescence. Intermediate the electron source and screen, but closely adjacent to the screen, is provided a parallax barrier to aid in color selection. In the color tube in greatest use, the parallax barrier acts as a shadow mask and comprises a relatively fragile foraminated portion attached to a relatively rigid frame. Support means, generally in the form of apertured leaf springs, are attached to the sides of the frame and cooperate with studs formed on an inner surface of the tube wall. The apertures in the foraminated portion are particularly aligned with the mosaic pattern of the screen and for successful maintenance of color purity it is necessary that this alignment remain relatively constant during tube operation. This condition has been difficult to maintain in the past because of the heat generated at the parallax barrier due to the bombardment thereon of the electron beam or beams. Misalignment occurred because of the differences in thermal expansion of the thin material in the foraminated portion and the heavier material in the frame. This differential in expansion during tube operation caused the foraminated portion to bow toward the screen thus disturbing the alignment.

To correct this problem, a recent innovation provides for intermediate mounting members between the frame and the supporting springs which comprise bimetallic elements having upper and lower portions connected by an expansion hinge. The lower portion is affixed to the frame and the upper portion has one end of a leaf spring attached thereto in such a manner that the free end of the spring engages a mating tapered stud which projects inwardly from an upstanding wall of the faceplate. In designs of this type the expanding hinge or loop projects inwardly toward the center of the tube and thus some modification of the frame is necessary to accept this projecting hinge.

Another innovation involved a similar intermediate mounting member utilizing a contracting or closing loop or hinge. In this type of structure the loop projected away from the frame and occupied the area between the frame and the faceplate sidewall, thus obviating any modification to the frame. This type, however, presents problems in smaller screen sizes of color tubes where the space between the frame and sidewall is apt to be critical.

OBJECTS AND SUMMARY OF THE INVENTION

Therefore, it is an object of this invention to enhance color television tube operation.

It is another object of the invention to obviate the difficulties inherent in the prior art structures.

It is another object of the invention to provide a temperature-compensating mounting means which is simple and inexpensive to manufacture and install.

These objects are accomplished in one aspect of the invention by the provision of a color cathode-ray tube containing, within an evacuated envelope, a mosaic cathodoluminescent screen, an electron source positioned remote from said screen, a parallax barrier mounted between the source and the screen but closer to the screen, and mounting means for releasably mounting the barrier within the tube. The barrier is comprised of a foraminated relatively fragile portion which is attached at its peripheral edge to one end of a circumferential sidewall of a relatively rigid frame. The circumferential sidewall of the frame extends substantially perpendicular to

the screen and the end of the wall remote from the foraminous portion has formed thereon an inwardly projecting flange. The mounting means comprises a plurality of substantially flat metallic elements positioned at spaced intervals about the frame and attached to the flange. Each of the elements has a depending spring which extends toward the screen between the circumferential wall of the frame and the envelope. The springs have means formed therein for engaging mating means formed on the envelope.

10

BRIEF DESCRIPTION OF THE DRAWINGS

FIG. 1 is an elevational sectional view of a typical color cathode-ray tube, greatly simplified;

FIG. 2 is a perspective view of the mounting means;

FIG. 3 is a sectional plan view of the faceplate portion of a color cathode-ray tube utilizing the invention;

FIG. 4 is a sectional plan view similar to FIG. 3 showing an alternate embodiment of the invention;

FIG. 5 is a sectional elevational view taken along the line 5—5 of FIG. 4;

FIG. 6 is a plan view taken along the line 6—6 of FIG. 5;

FIG. 7 is a plan view similar to FIG. 6 but illustrating the element of FIG. 2; and

FIG. 8 is a partial, sectional elevational view showing an alternate mounting embodiment.

DESCRIPTION OF THE PREFERRED EMBODIMENTS

For a better understanding of the present invention, together with other and further objects, advantages, and capabilities thereof, reference is made to the following disclosure and appended claims in connection with the above-described drawings.

Referring now to the drawings with greater particularity, there is shown in FIG. 1 a simplified view of a typical color cathode-ray tube 10 having an evacuated envelope 12. A faceplate portion 14 seals one end of envelope 12 and a reduced diameter neck 16 seals the other end. An electron gun 18 is positioned within the neck for directing one or more beams of electrons to a mosaic phosphor screen 20 which is formed on the interior surface 22 of faceplate 14. A parallax barrier 24, to aid in color selection, is removably mounted adjacent the phosphor screen 20.

The parallax barrier, which in this instance is a shadow mask, comprises a relatively fragile-foraminated portion 26 attached at its peripheral edge 28 to one end of a circumferential sidewall 30 of a relatively rigid frame 32. The sidewall 30 extends substantially perpendicular to the screen 20 and is parallel to an upstanding circumferential wall 34 of envelope 12 which projects from faceplate 14. The end of wall 30 remote from the foraminated portion 26 is provided with an inwardly projecting flange 36.

The novel-mounting means 38 of this invention is shown

isolated in FIG. 2 and comprises a substantially flat bimetallic element 40 comprised of two-contiguous layers 42 and 44 having different thermal coefficients of expansion. Layer 44 has the higher coefficient of expansion and can be, for example, a composition of 22% Ni, 3% Cr, with the balance Fe. Layer 42 has a lower coefficient of expansion which should be substantially zero over the temperature range of normal tube operation (22°-75° C. at the mask) and can be, for example, Invar, which has composition of 36% Ni and the balance Fe. Such a material is available as Chace No. 2400 bimetal from the W. M. Chace Co. Element 40 is substantially rectangular and has short edges 46, 48; a long front edge 50 and a long back edge 52; and upper and lower surfaces 54, 56. A depending spring 58 is attached to element 40 and, as is shown in FIG. 2, the attachment is accomplished via a spring flange 60 fixed to upper surface 54 as by welding. This is an exemplary attachment only, and the spring flange can be attached to lower surface 56 or the spring can be formed without the flange and be connected directly to edge 50. Spring 58 is substantially trapezoidal and is provided at its free end 62 with an aperture

55

60

65

70

75

64 for engaging a projecting stud 66, a plurality of which are positioned in wall 34 of tube 10.

The mounting means 38 of this invention can be utilized in either of the two most prevalent supporting systems currently in use, namely: a three point system and a four point system. Each of these systems will be discussed in turn.

In the three point system, as illustrated in FIG. 3, a first mounting means 38 is positioned substantially on the vertical axis of the tube 10. Bimetallic element 40 is fixedly attached to flange 36 of frame 32 with the high-expansion material lowermost and adjacent the flange 36. Attachment is made at a plurality of points, indicated as x's in the drawing, and the attaching means can be any suitable type, such as welds. For the first mounting means 38, the welds are all positioned a substantially equal distance in from back edge 52.

The remaining two-mounting means 38 are positioned opposite one another on the short sides of frame 32, some distance below the horizontal axis of tube 10. Ideally, they are about 110° from the mounting means located on the vertical axis. The mounting means on the short sides of the frame are identical to the first-mentioned means on the vertical axis of tube 10 except that the attachment points thereon are spaced progressively further from the back edge 52 of the elements 40 as the distance from the horizontal axis increases. This reduces the active length of the bimetal and compensates for the fact that the side mounted elements are not on the horizontal axis.

The four point suspension system is shown in FIG. 4 and comprises four-mounting means 38, two being mounted substantially on the vertical axis and two being mounted on the horizontal axis. With this type of equalized support, all of the individual attachment means for the elements 40 are equally spaced from the back edge 52.

During operation of the tube heat generated in the mask and frame by bombardment of the electron beam or beams thereon causes the mask 26 to expand. Without some form of compensation, the expansion destroys the critical alignment between the holes in the mask and the mosaic phosphor screen, resulting in a loss of purity. With the mounting means of this invention, however, this heat-generated distortion is corrected as is shown in FIG. 5. As the heat builds up in the mask and frame it is transferred to the bimetallic element 40 which bends as shown because of the differential in thermal expansion between the layers. Since one point of the system, namely the spring aperture and the fixed stud 66 is completely stationary, this bending movement of the bimetal is transferred into downward movement of the mask and frame, which serves to maintain alignment.

An alternate embodiment of the invention is shown in FIG. 8. Herein, the flange 36 is provided, at least at those areas whereat elements 40 are to be connected, with a raised protuberance or rib 68. This insures that the bimetal is not being pressed against the frame, say from heat-caused distortion during welding. If the bimetal were being pressed against the frame then the first say, 20° of heat, might serve only to relieve the tension the bimetal was originally in. In such instance, the degree of movement obtainable might not be sufficient to correct completely for the misalignment occurring during tube operation.

While various types of bimetallic elements can be used, excellent results have been achieved using Chace Type 2400. The element 40 is approximately 1.5 inches long and 1 inch

wide by 0.060 inch thick. The spring material can be Inconel X 750, 1.5 inches at the widest part of the trapezoid and 0.5 inch at the narrow end.

Thus, it will be seen that there is here provided a temperature-compensating mask-mounting system with many advantages over the prior art. It is simple and inexpensive to manufacture and requires no changes or modification to be made to the existing mask-frame structure.

While there have been shown and described what are at present considered the preferred embodiments of the invention, it will be obvious to those skilled in the art that various changes and modifications may be made therein without departing from the scope of the invention as defined by the appended claims.

15 I claim:

1. A color cathode-ray tube containing, within an evacuated envelope, a mosaic cathodoluminescent screen, an electron source positioned remote from said screen, and a parallax barrier mounted between said source and said screen but closer to said screen, said parallax barrier having a foraminated relatively fragile portion attached at its peripheral edge to one end of a circumferential sidewall of a relatively rigid frame, said circumferential sidewall extending substantially perpendicular to said screen and having an inwardly projecting flange substantially parallel to said screen formed on the end of said wall remote from said foraminous portion, and means for releasably mounting said barrier within said tube, said means comprising: a plurality of flat metallic elements positioned at spaced intervals about said frame and attached to said flange, each of said elements having a depending spring attached thereto and extending toward said screen between said circumferential wall of said frame and said envelope and having means formed therein engaging mating means formed on said envelope, said flat metallic elements being composed of two contiguous layers of material, one of which has a higher coefficient of thermal expansion than the other, and said higher coefficient material being adjacent said flange.

2. The invention of claim 1 wherein said flat metallic elements are substantially rectangular having a long side and a short side and said long side extends approximately parallel to said flange.

3. The invention of claim 1 wherein said flat metallic elements are four in number and said spaced intervals are approximately 90° apart, and each of said elements is attached to said flange by a plurality of attachment means, each of said attachment means being spaced inwardly from the back edge of said elements a substantially equal distance.

4. The invention of claim 1 wherein said flat metallic elements are three in number, a first one of said elements being positioned substantially on the vertical axis of said flange and a second and third of said elements being oppositely disposed on said flange and being positioned below the horizontal axis of said flange, each of said elements being attached to said flange by a plurality of attachment means, the attachment means on said first element being spaced inwardly from the back edge of said first element a substantially equal distance and the attachment means on said second and third elements being spaced progressively further from the back edge of the elements as the distance from said horizontal axis increases.

5. The invention of claim 1 wherein said depending spring is substantially trapezoidal in configuration.
